UNITED STATES PATENT OFFICE.

CONRAD D. YOUNGBERG, OF WOODSTOCK, ILLINOIS, ASSIGNOR TO WOODSTOCK TYPEWRITER COMPANY, OF WOODSTOCK, ILLINOIS, A CORPORATION OF ILLINOIS.

CASE-SHIFT MECHANISM FOR TYPEWRITERS.

Application filed January 2, 1925. Serial No. 31.

This invention relates to mechanism for effecting case shifting of power driven apparatus such as that shown in the application of Otto A. Hokanson, Serial No. 732,615, filed August 18, 1924, granted January 18, 1927, as Patent No. 1,614,475, for an improvement in power actuated typewriters. The present invention has for its object the provision of case shift mechanism which shall be of improved construction and operation and in which the movement and release of the movable part shall be under the control of the operator and shall be produced with a minimum amount of exertion. The invention is exemplified in the combination and arrangement of parts shown in the accompanying drawings and described in the following specification and it is more particularly pointed out in the appended claims.

In the drawings:

Figure 1 is a vertical sectional view of a typewriting machine showing one embodiment of the present invention; and

Fig. 2 is a view similar to Fig. 1, showing a slightly different form of the invention.

Referring first to Fig. 1, the numeral 10 designates the frame of a typewriter machine which is provided with a rotary power drum 11 for actuating the type bars in the manner described in the application referred to above. At one side of the frame 10 and at one end of the drum 11 a pinion 12 is secured to the drum 11 which meshes with an idler pinion 13 which in turn drives a larger gear 14. The gear 14 is mounted on a stud shaft 15 secured to the side of the frame 10 and the pinion 13 may be journaled on a bracket 16 also projecting from the side of the frame 10. The gear 14 has a ratchet wheel 17 formed integral therewith and disposed in registration with a tooth 18 on an actuator bar 19. The tooth 18 is normally held upwardly and rearwardly by a spring 20. The rear end of the actuator 19 is pivoted at 21 to a rock arm 22 journaled at 23 on bracket 24 extending from the side of the frame 10. A link 25 is pivoted at 26 to the arm 22 and the rear end of the link 25 is pivoted at 27 to a case shift frame 28. The shift frame 28 carries a shift rail 29 by means of which the platen is raised for changing from lower to upper case. The frame 28 carries a stop 30 adjustably mounted thereon and having one face thereof 31 arranged to bear against a detent 32. The detent 32 is

provided with a shoulder 33 movable into engagement with the shoulder 34 on the stop 30 to retain the case shift frame in its uppermost position. The detent 32 is pivotally mounted at 35 and is provided with a spring 36 normally urging the detent against the face 31. A shift lever 37 is pivotally mounted at 38 and is provided with a contact finger 39 engaging a lug 40 on the actuator 19. When the shift lever 37 is depressed a sufficient amount to bring the tooth 18 into the path of the tooth on the ratchet wheel 17 the actuator 19 will be drawn forwardly by the rotation of the ratchet wheel 17 so that the link 25 will move the shift frame 28 about its pivot 41 until the shoulder 33 on the detent 32 engages the shoulder 34 on the stop 30. This will lock the shift frame in its uppermost position where it will remain until the detent 32 is released in the manner to be described. The actuator tooth 18 will be moved into contact with a release screw 42 which will throw the actuator out of engagement with the ratchet wheel 17 and cause it to be drawn upwardly by the spring 20 out of the path of the teeth on the wheel 17.

The detent 32 is provided with a downwardly extending arm 43 which carries a link 44 pivoted at 45 thereon. The forward end of the link 44 is provided with a nose 46 disposed adjacent the teeth of the ratchet wheel 17. A plate 47 is adjustably mounted on the link 44 and is provided with a cam lug 48 which engages a screw 49 adjustably mounted in a guide plate 50. When the detent 32 is in the position shown in Fig. 1 with the link 44 retracted, the cam face 48 cooperating with the screw 49 holds the nose 46 out of the path of the teeth on the ratchet wheel 17. When the detent 32 rotates upon its pivot 35 to lock the shift frame in its uppermost position the cam face 48 will move forward to permit the nose 46 to swing upwardly into contact with the teeth on the ratchet wheel 17. So long as the shift lever 37 is depressed, however, a pin 51 on the side of the lever 37 will engage the link 44 and prevent the nose 46 from swinging into engagement with the ratchet wheel 17. As soon as the shift lever is released, however, the link 44 will be free to swing upwardly under the influence of a spring 52 connected therewith so that the nose 46 will be brought into engagement with the teeth of the ratchet wheel 17. This will move the link 44 rearwardly

- so as to disengage the shoulder 33 from the stop 30 and permit the shift frame 28 to return to its lowermost position. The same rearward movement will bring the cam face 48 into engagement with the screw 49 so as to retain the nose 46 out of the path of the teeth on the ratchet wheel 17. It will thus be seen that on a slight depression of the shift key the carriage will be automatically raised to effect a case shifting movement. The power for raising the carriage is furnished from the power driven roller 11, the movement of the shift key alone being sufficient to move the actuator 19 into engagement with the teeth of the ratchet wheel 17. As long as the shift key is held in its depressed position the platen will remain in its upper case position but as soon as the shift key is released the locking mechanism will be disengaged by the power driven ratchet wheel 17 so that the parts will be restored to their lower case position without further effort on the part of the operator. It will be noted that the ratchet wheel 17 is driven at a lower speed than is the main power drum 11. In some cases this may be found desirable because of the greater weight of the parts moved during case shifting than that of the parts actuated for writing.
- In the form of the invention shown in Fig. 2 the parts are similar to those described in connection with Fig. 1 except that the actuator 19 for the case shift mechanism is arranged to directly engage the main power drum 11 and the nose piece 46 of the release link 44 also engages the main power drum 11. Where rapid movement of the case shift mechanism is desired and where the weight of the shifted parts does not interfere with this rapid operation, the arrangement shown in Fig. 2 may be employed.
- A single link 44 is provided at one side of the machine only, but it may be operated by shift levers 37 at either side of the machine. These levers are connected by a rock shaft 55 and arms 56, the arms being fixed to the rock shaft and pivoted, one to each of the shift levers 37. In this way depression of either shift lever will actuate the shift mechanism as the two shift levers are constrained to act in unison.
- I claim:
1. In a typewriting machine, a case shift member, a continuously operating power drive, an actuator for said case shift member, a key lever for establishing connection between said power drive and actuator, and power actuated means other than said actuator for controlling the return of said case shift member after operation of said actuator.
  2. In a typewriter, a case shift member, a power drive, an actuator for said case shift member, a key lever for effecting operative connection between said actuator and power drive to move said case shift member, a latch

for retaining said case shift member in the position to which it is moved by said actuator, means for releasing said latch, means controlled by said key lever for connecting said latch releasing means with said power drive to effect release of said latch, and means operated by said key lever for preventing operation of said releasing means while said key lever is depressed.

3. In a typewriter, a case shift member, a power drive comprising a continuously rotating toothed wheel, an actuator for said case shift member, a key lever for moving said actuator into engagement with said toothed wheel to effect a case shift movement, a latch for retaining said case shift member in its shifted position, means for releasing said latch, and means controlled by said key lever for effecting operative connection between said latch releasing means and toothed wheel upon release of said key lever to effect release of said latch.

4. In a typewriter, a case shift member, key controlled power actuated means including a power drive for effecting a case shift movement of said member, a latch for retaining said member in its shifted position, an actuator for said latch movable into engagement with said power drive, means for retaining said actuator out of engagement with said power drive when said latch is released, and key controlled means for preventing engagement of said power drive and actuator when said latch is engaged and said key lever is depressed but permitting engagement of said power drive and actuator to release said latch upon the release of said key lever.

5. In a typewriter, a case shift member, a latch for retaining said case shift member in shifted position, a power driven member, a link connected with said latch and having means thereon for engaging said power driven member, a stop for holding said link out of operative engagement with said power driven member when said latch is in released position but permitting movement of said link into engagement with said power driven member when said latch is in engaged position, a key lever, and means on said key lever for holding said link out of operative engagement with said power driven member when said key lever is depressed but arranged to permit the engagement of said link with said power driven member when said key lever is released and said latch is in engagement with said case shift member.

6. In a typewriter, a pivoted case shift member, a pivoted latch for holding said case shift member in one position, a power actuated drive, a link connected with said case shift member, key controlled means for establishing operative connection between said link and said power drive, a link con-

nected with said latch and key controlled means for effecting operative connection between said last named link and said power drive.

- 5 7. In a typewriter, a case shift member, a power drive comprising a continuously rotating toothed wheel, an actuator for said case shift member comprising a link having a tooth for engaging said wheel, a latch for 10 said case shift member, means for releasing said latch comprising a link having a tooth for engaging said wheel, and a key lever for effecting engagement between the tooth on said actuator and the teeth on said wheel to 15 effect case shift movement when said key lever is depressed, said key lever operating to establish connection between the teeth on said toothed wheel and the tooth on the releasing means for said latch to effect release 20 of said latch when said key lever is released.
8. In a typewriter, a power actuated member for actuating a portion of a typewriter mechanism, a second power actuated member, reduction gearing interposed between

said power actuated members, case shift 25 mechanism, a key lever for effecting connection between said second power actuated member and said case shift mechanism, a latch for automatically retaining said case shift mechanism in its shifted position, means 30 for releasing said latch, and means for effecting connection between said releasing means and said second power actuated member upon release of said key lever.

9. In a typewriting machine, a case shift 35 member mounted to rock about a horizontal axis, a continuously operating power drive, an actuator for rocking said case shift member, a key lever for establishing connection between said power drive and actuator, and 40 power-actuated means independent of said actuator for controlling the return of said case shift member after operation of said actuator.

In testimony whereof I have signed my 45 name to this specification on this 29th day of December, A. D. 1924.

CONRAD D. YOUNGBERG.
